FILM PRINTING MACHINE

Jack Howard Coote and Arthur Philip Jenkins,
London, England, assignors to Dufay-Chromex
Limited, London, England, a British company

Application August 9, 1948, Serial No. 43,258
In Great Britain May 14, 1947

6 Claims. (Cl. 95—75)

1

This invention relates to a film-printing machine which is capable of use in making contact prints through the thickness of the film base.

Two general types of film-printing machine are available. In one the light output is maintained substantially constant and the amount of light reaching the exposure plane is controlled by means of a variable iris type of aperture and diffusers are inserted between the iris and the exposure plane so as to secure a substantially even illumination at the latter. When this system is used to print colour records the slight but noticeable differences in evenness in the records printed at differing light apertures may result in uneven colouring of the print. Moreover, on account of the use of the diffusers it is not possible to obtain satisfactory prints by printing through the thickness of the film base.

In the second general type in order to dispense with apertures and diffusers provision is made for varying the intensity of the light by providing resistances which may be brought into and taken out of circuit in predetermined manner. However, in printing images whose densities have to be accurately controlled, as, for example, in colour cinematography, it is found not to be readily feasible to control the light output within the desired limits owing to such factors as the temperature coefficient of the resistances and possible change in applied voltage with change in load due to the changing of the resistance in circuit.

The present invention seeks to overcome these difficulties by providing a printer in which the light output of the printer is maintained substantially constant during printing operations and the time of exposure is varied in a predetermined manner. Accurate control of the printing operation has been found possible in this way and printing through the film base can be readily carried on.

According to the present invention a film-printing machine comprises means for varying in predetermined manner the time interval during which a substantially parallel beam of light of substantially constant intensity is incident upon a film-exposure plane.

The apparatus in accordance with the present invention may comprise an optical system for producing a substantially parallel beam of light, a first rotatable cut-off shutter adapted to interrupt said beam of light, means for driving the rotatable shutter, a second rotatable cut-off shutter adapted to interrupt said beam of light, means for driving the second rotatable cut-off shutter, film-confining means including an exposure aper-

2

ture in the path of said beam of light, film transport means associated with the film-confining means and manually operable means for varying the phase relationship between the two rotatable cut-off shutters so as to vary in predetermined manner the time interval during which light passes both shutters and is incident upon a photographic negative being printed during its passage through the film-confining means.

10 According to a feature of the invention the film-transport means is driven by the same power source as the first rotatable cut-off shutter.

In one form of apparatus in accordance with the invention provision is made for mounting a substantially point source of light and this is mounted in spaced relation to a lens system so that the light passing therethrough from the point source is rendered substantially parallel. The path of the resulting beam of light is intercep-

15 toed by two separately rotatable shutters. These shutters may be of the type normally used on cinematograph cameras. They are so mounted that during rotation of each one the apertured portion passes through the path of the beam of light. The shutters are mounted for rotation independently of each other and may, for example, be driven by a pair of electric motors which are electrically interlocked so that one motor is the "master" motor while the other is the

20 "follower" motor and they rotate in synchronism. The two cut-off shutters are so set with respect to each other that during a part of one complete revolution light passes both. By varying the phase relationship between the two shutters 25 the angle over which light passes both, and thus the time interval during which light passes may be varied. Accordingly provision is made for varying the phase of the follower motor by providing for rotation of the stator of that motor 30 to any desired extent at any predetermined time when the machine is in use.

The invention will now be described with reference to the accompanying drawings in which:

Figure 1 is a front elevation of a film printer 45 constructed in accordance with the invention showing the paths which the positive and negative films follow.

Figure 2 is a sectional view along the line A—A' of Figure 1 and

50 Figure 3 is a detailed view of one form of manual means for varying the phase relationship of the rotatable cut-off shutters.

Referring to Figure 1 of the drawings positive stock for printing is drawn from the reel 1 to the film printing plane 3 by the sprocket 2 and

55

is then drawn away by the sprocket 4 and taken up upon reel 5. Similarly negative film to be printed is drawn from reel 6 by sprocket 1 to the film printing plane 3 and is then drawn away by the sprocket 8 to the negative take up reel 9. Film transport means for moving both negative and positive films past the exposure aperture is housed under the casing 10 and may be of conventional type. Guide rollers 11, 12, 13 and 14 are provided along the path of the positive being printed and similar rollers 15, 16, 17 and 18 are also provided along the path of the negative.

Referring more particularly to Figure 2 the lamp 20 provides a substantially constant source of illumination. There may be included in circuit with the lamp one or more variable resistances by variation of which compensation may be applied for the tendency of the light output of the lamp to diminish with age or through other causes: this is not shown upon the drawings. A collimating lens system, shown at 21 is provided for producing a parallel beam of light, the lamp 20 being so inclined with respect thereto that the line filament appears substantially as a point source. Light from lamp 20 after passing collimating lens system 21 is incident upon a front surface reflecting mirror 22 which is inclined at an angle of 45° with respect to the axis of the beam of light.

Before reaching the surface of mirror 22 the light has to pass the plane of a rotatable shutter 23 driven from the follower motor 24, the stator of which motor is attached to and rotatable with a gear wheel 25 the position of which is manually controlled by means hereinafter to be described. After reflection at mirror 22 the light reaches the plane of the second rotatable shutter 26. The shutter 26 is mounted upon the shaft 27 of the master motor 28. Also mounted upon shaft 27 are cams 29 which operate the film transport mechanism housed within the housing 10. Shutter 26 being connected to the master motor 28 rotates at constant speed. Shutter 23 being mounted upon the shaft of follower motor 24 can have its phase varied with respect to that of shutter 26 and in this way the interval during which light passes both shutters can be varied.

One method of controlling the phase relationship of the two shutters is shown in Figure 3. A pointer arm 30, manually operable by a handle 30A, is provided mounted upon a pivot. On the front of the printer a scale 32 (Figure 1) is provided having a number of setting positions indicated thereon. The pivot is adapted to cooperate with an arm 33 so as to impart a longitudinal to and fro movement thereto through the intervention of a rack and pinion device 31, 31A. The arm 33 which is supported in guide blocks 60 and contains a link 34 pivoted at 34A, is provided with a roller 35 at one end thereof as well as an articulately mounted rod 36 which carries a spring 37 always held in compression thereon. The upper end of rod 36 is carried in the bracket 38 which is mounted upon base 39 which is itself pivotally supported at 40.

The roller 35 is normally urged into the bottom of a V-groove 42 formed as a part of a swinging arm 41. Arm 41 is secured to base 39 as by rivets 43 and at its other end 44 is pivoted to a link 45, which is pivoted to arm 46 at 47. The arm 46 which is mounted in guide blocks 59, is provided with an electromagnetic release generally designated 48. Arm 46 also carries a rack 49 which meshes with the gear wheel 25 which rotates the stator of follower motor 24.

The electromagnetic release 48 is operated by 75

means of an indication provided upon the negative being printed. This may take the form of a notch in the side of the film. A roller is urged into contact with the side of the film and upon entering a notch closes the contacts 50 of an electrical circuit. In parallel with the contacts 50 are a resistance 51 and capacitance 52 so as to minimize sparking across the contacts. In series are a switch 53, a source of E. M. F. 54 and a solenoid mounted within the housing 55. The plunger 56 is mounted within a guide 57 which is surrounded by the solenoid. Plunger 56 is normally urged upwards by the spring 57 into frictional engagement with the arm 46. The frictional engagement is sufficient to hold the arm 46 against longitudinal movement when the roller 35 is part way up either of the inclined planes of the V-groove 42. Such frictional engagement is only interrupted when the circuit is momentarily completed through the contacts 50 and the solenoid in housing 55 is actuated. During such interruption the downward thrust of spring 37 urges the roller 35 to the bottom of the V-groove 42 and in so doing drives the gear wheel 25 into a new position in which it is maintained by the frictional engagement between plunger 57 and arm 46 until the circuit is again broken.

Instead of having a notch in the side of the film a metal insert may be provided which momentarily completes the circuit and actuates the solenoid.

The exposure intervals are determined in advance of printing and translated into the corresponding indications upon scale 32. A length of leader film should be provided so that the motors have reached the constant printing speed before the negative to be printed commences to run through the apparatus which has been set at the first printing indication so that the follower motor then adjusts itself in accordance with that indication when the frame opposite which the notch is cut in the negative is moved forward to the exposure position and in so doing closes the contacts 50 and drives the gear wheel 25 to the corresponding position. As soon as the follower motor has been driven to the desired position the next manual presetting of arm 30 may be made and operation then continues until printing is completed or is interrupted for any reason.

The cut-off shutters need not be driven by electric motors as just described although these are very convenient and therefore preferred for this purpose. Other means may also be used for transmitting the presetting to the variable shutter. Thus the transmission member may operate gearing or a worm and collar device may be employed.

The shafts carrying the cut-off shutters may be mounted concentrically if desired but they are preferably separately mounted and each connected to the shaft of an electric motor as already indicated.

Since a substantially parallel beam of light is employed the apparatus in accordance with the present invention may be used for contact printing through the base of the film. The apparatus may therefore be used for printing the innermost layer of a multilayer material through the emulsion support. Moreover, since diffusers are not employed a high intensity illumination at the exposure plane can be secured without the use of a lamp of abnormally high wattage as the light source. In addition fine grain materials may be satisfactorily printed using the improved apparatus.

We claim:

1. A continuous step-contact printing machine comprising a casing, a mount for a source of light within said casing, an optical system for producing a parallel beam of light mounted in an aperture in said casing, a film exposure aperture in the path of said parallel beam of light, a first rotatable cut-off shutter so disposed as to interrupt the path of light from said source to said exposure aperture during a part of each rotation thereof, an electric motor for continuously driving said first shutter, a second rotatable cut-off shutter so disposed as to interrupt the path of light from said source to said exposure aperture during a part of each rotation thereof, an electric motor for continuously driving the second rotatable cut-off shutter in synchronism with the first shutter, a single film transport mechanism for intermittently and simultaneously feeding successive frames of both a transparent photographic negative and unexposed photographic film in contact through said film exposure aperture while said beam of light is interrupted by at least one of said shutters and means responsive to an indication provided upon said negative film for varying in a predetermined manner the phase relationship of said second motor with respect to said first motor and thereby to vary between the printing of successive frames of said negative the time interval during which light passes both shutters and is incident upon successive frames of said negative.

2. A continuous step-contact film printing machine according to claim 1 in which the means responsive to an indication provided upon said negative film for varying in a predetermined manner the phase relationship of the two motors is restrained from change by frictional engagement with a member whose engagement therewith is interrupted by the activation of a solenoid.

3. A machine according to claim 2 in which activation of the solenoid is effected by the closure of an electric circuit by means of an indicator carried by the film being printed.

4. A continuous step-contact printing machine comprising a casing, a mount for a source of light within said casing, an aperture in said casing, an optical system mounted upon said casing for collimating a beam of light passing through said aperture, film confining means comprising an exposure aperture in the path of said collimated beam of light, a first rotatable cut-off shutter so disposed as to interrupt the path of light from said source to said exposure aperture during a part of each rotation thereof, an electric motor

55

for continuously driving said first shutter, a second independently mounted rotatable cut-off shutter so disposed as to interrupt the path of light from said source to said exposure aperture during a part of each rotation thereof, an electric motor for continuously driving said second shutter in synchronism with the first shutter, film transport means for intermittently and simultaneously feeding successive frames of transparent negative stock and positive stock in contact through said film confining means while said beam of light is interrupted by at least one of said shutters and means responsive to an indication provided upon said negative stock for varying in a predetermined manner the phase relationship of said second motor with respect to said first motor and thereby to vary between the printing of successive frames of said negative stock the time interval during which light passes both shutters and is incident upon successive frames of said negative stock.

5. A continuous step-contact film printing machine according to claim 4 in which the means responsive to an indication provided upon said negative film for varying in a predetermined manner the phase relationship of the two motors is restrained from change by frictional engagement with a member whose engagement therewith is interrupted by the activation of a solenoid.

6. A machine according to claim 5 in which activation of the solenoid is effected by the closure of an electric circuit by means of an indicator carried by the film being printed.
